Primary Examiner — Joseph Kukella*Assistant Examiner* — Arva P Adams(74) *Attorney, Agent, or Firm* — RatnerPrestia(57) **CLAIM**

The ornamental design for an ice coffee maker, as shown and described.

DESCRIPTION

FIG. 1 is a perspective view of an ice coffee maker showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawings are for the purpose of illustrating unclaimed portions of the ice coffee maker and form no part of the claimed design, and the dash-dot-dash broken lines illustrate the boundary of the claimed design.

1 Claim, 7 Drawing Sheets(56)
